UNITED STATES PATENT OFFICE

132,204

DESIGN FOR A SERVICE FLAG

James W. Mellen, Los Angeles, Calif.

Application February 6, 1942, Serial No. 105,661

Term of patent 3½ years

To all whom it may concern:

Be it known that I, James W. Mellen, a citizen of the United States, residing at Los Angeles, in the county of Los Angeles and State of California, have invented a new, original, and ornamental Design for Service Flags, of which the following is a specification, reference being had to the accompanying drawing, forming part thereof.

In said drawing the figure is a front view of a service flag showing my new design.

I claim:

The ornamental design for a service flag, as shown.

JAMES W. MELLEN.
